REFRIGERANT EVAPORATOR

Leonard W. Atchison, Schenectady, N. Y., assignor to General Electric Company, a corporation of New York

Application September 7, 1940, Serial No. 355,758

3 Claims. (Cl. 62—126)

My invention relates to evaporators for refrigerating machines and particularly to refrigerant evaporators of the non-flooded type.

In the operation of refrigerant evaporators of the non-flooded type, difficulty is sometimes encountered because of the "slugging back" of liquid refrigerant through the suction line to the compressor. The admission of liquid refrigerant to the compressor is objectionable since it reduces the operating efficiency of the system and also produces noise and may cause breakage of the valves. In order to prevent the admission of slugs of refrigerant to the suction line, various forms of liquid traps arranged externally of the evaporator have been employed.

It is an object of my invention to provide a refrigerant evaporator having incorporated therein an improved arrangement for preventing the discharge of liquid refrigerant from the evaporator.

Another object of my invention is to provide an evaporator conduit having an improved arrangement for checking the flow therethrough of slugs of liquid refrigerant.

Further objects and advantages of my invention will become apparent as the following description proceeds and features of novelty which characterize my invention will be pointed out with particularity in the claims annexed to and forming a part of this specification.

For a better understanding of my invention, reference may be had to the accompanying drawing in which Fig. 1 is a sectional front elevation view of a household refrigerator provided with an evaporator embodying my invention, and Fig. 2 is an enlarged sectional view on the line 2—2 of Fig. 1.

The evaporator shown in the accompanying drawing comprises a sheet metal structure provided with a sinuous indentation forming a refrigerant conduit extending from an inlet near the bottom of the evaporator to an outlet near the top thereof. In order to prevent slugs of liquid refrigerant produced by sudden surges from being discharged from the evaporator and admitted to the suction line, there are provided a plurality of pockets arranged in line with the direction of flow of refrigerant so that the slugs of liquid refrigerant tend to flow into the pockets due to their momentum while the gaseous refrigerant flows on through the conduit. The liquid refrigerant will then flow back into the conduit by gravity after the initial surge has thus been checked.

Referring now to the drawing in Fig. 1, I have

shown a household refrigerator comprising a cabinet 18 having a food storage compartment 11 surrounded by thermally insulated walls 12, access to the compartment being had through a suitable door (not shown) provided in the front of the cabinet. A compartment 13 is provided in the lower portion of the cabinet and contains a refrigerant condensing unit comprising a hermetically sealed casing 14 containing a motor driven refrigerant compressor arranged to supply compressed refrigerant through a discharge line 15 to a condenser 16. The condenser 16 and the casing 14 are cooled by operation of a fan 17 driven by a motor 18 secured to the casing 14. Air for cooling the casing and the condenser is admitted to the compartment 13 through an opening provided with louvers 19 and is discharged therefrom through an opening provided with louvers 20. The compressed refrigerant in the condenser 16 is cooled and liquefied and flows to a liquid receiver or float valve chamber 21. When a predetermined amount of liquid refrigerant has collected in the receiver 21, a float therein rises to open a valve, and the refrigerant is then discharged through a liquid line 22 and flows upwardly to a sinuous conduit 23 of substantially uniform cross section throughout its length and formed in a sheet metal evaporator 24 arranged within the compartment 11. Liquid refrigerant in the evaporator 24 is vaporized by the absorption of heat from the air within compartment 11 and the vaporized refrigerant is withdrawn from the evaporator through a suction line 25 by operation of the compressor within the casing 14. During normal operation of the evaporator, liquid refrigerant is admitted to the lower end of the conduit and flows upwardly through the conduit assisted by gaseous refrigerant vaporized from the liquid. At times, particularly when the float valve is first opened, there may be a rush or surge of liquid refrigerant through the conduit; this tends to discharge slugs of liquid to the suction line. In order to prevent slugs of liquid refrigerant from reaching the outlet of the evaporator, I have provided a plurality of chambers or pockets 26 arranged in communication with the conduit 23 at the return bends which connect the several horizontal runs of the conduit. The chambers 26 are connected to the bends by short passages 27 extending tangentially of the respective return bends with which they are connected so that any slugs of liquid refrigerant flowing around the bend will tend to be thrown by their momentum through the passages 27 and into the

chambers 26. The arrangement of the chambers 26 therefore checks any sudden surge of slugs of liquid refrigerant through the evaporator. Since the chambers 26 are arranged above the portions of the conduit 23 to which they are connected, the liquid refrigerant which enters the chambers 26 flows back into the conduit where it is vaporized in the usual manner.

The construction of the chambers 26 is more clearly shown in Fig. 2 in which the evaporator is shown as constructed of two metal sheets 28 and 29. The sheet 29 has been illustrated as a portion of the metal inner liner of the compartment 11. The sheet 28 is provided with suitable indentations forming the sinuous conduit 23 and also the chambers 26 and their passages 27, and the two sheets are welded or otherwise suitably secured together around the edge of the sheet 28 and between the indentations to make the evaporator pressure-tight. I prefer to form the chambers 26 near the curved end portions or return bends of the conduit 23 in order to make use of the momentum of the liquid refrigerant to separate the liquid from the stream of gaseous refrigerant flowing through the evaporator. It will be readily understood that, although the slugs of liquid are thrown into the chambers 26, the gaseous refrigerant continues in its passage through the conduit 23.

It will be apparent from the foregoing that I have provided an effective and easily constructed arrangement for preventing "slugging back" or the discharge of liquid refrigerant from an evaporator which maintains a high operating efficiency of the system and minimizes the danger of damage to the compressor mechanism due to the presence of liquid refrigerant in the suction line.

While I have shown a particular embodiment of my invention in connection with a household refrigerator, other applications will readily be apparent to those skilled in the art. I do not, therefore, desire my invention to be limited to the particular construction shown and described, and I intend in the appended claims to cover all modifications within the spirit and scope of my invention.

What I claim as new and desire to secure by Letters Patent of the United States is:

1. A refrigerant evaporator comprising a conduit having an inlet and an outlet, said conduit having a substantially uniform cross section throughout its length, means providing a chamber in direct communication with an intermediate portion of said conduit, said chamber being arranged in line with the direction of refrigerant flow in said portion of said conduit whereby any slugs of liquid refrigerant flowing through said portion of said conduit will tend to be thrown by their momentum from said conduit into said chamber.

2. A refrigerant evaporator comprising a conduit having a curved portion and having an inlet and an outlet, said conduit having a substantially uniform cross section throughout its length, means providing a chamber in direct communication with said curved portion of said conduit, said chamber being arranged in a tangential line with respect to said curved portion of said conduit whereby any slugs of liquid refrigerant flowing through said curved portion will tend to be thrown by their momentum from said conduit into said chamber.

3. A refrigerant evaporator comprising a conduit having an inlet and an outlet, said conduit

having a substantially uniform cross section throughout its length, means providing a chamber above an intermediate portion of said conduit and in direct communication therewith, said chamber being arranged in line with the direction of refrigerant flow in said portion of said conduit whereby any slugs of liquid refrigerant flowing through said portion will tend to be thrown by their momentum from said conduit upwardly into said chamber.

4. A refrigerant evaporator comprising a sinuous conduit having a plurality of turns and having an inlet and an outlet, said conduit having a substantially uniform cross section throughout its length, means providing chambers in direct communication with said conduit at a plurality of said turns, each of said chambers being arranged in a tangential line with respect to the flow of the refrigerant in its respective turn whereby any slugs of liquid refrigerant flowing through said turns will tend to be thrown by their momentum from each of said turns into the respective one of said chambers communicating therewith.

5. A refrigerant evaporator comprising a sinuous conduit providing a plurality of horizontal runs connected by return bends and arranged in an upwardly extending plane, said conduit having an inlet near the bottom thereof and an outlet near the top thereof, means providing chambers in direct communication with said conduit at a plurality of said bends, each of said chambers being arranged above and in direct communication with its respective one of said bends in a line tangential to the direction of flow of refrigerant in said respective bend whereby any slugs of liquid refrigerant flowing through said bends will tend to be thrown by their momentum from said bends into the respective chambers in communication therewith, the liquid refrigerant thrown into said chambers thereafter flowing by gravity back to said conduit.

6. A refrigerant evaporator comprising a conduit having an inlet and an outlet and an intermediate curved portion, said conduit having a substantially uniform cross section throughout its length, means providing a chamber and a direct connection between said chamber and said curved portion of said conduit, the direct connection between said chamber and said conduit being in a tangential line with respect to said curved portion of said conduit whereby any slugs of liquid refrigerant flowing through said curved portion will tend to be thrown by their momentum from said conduit into said chamber.

7. A refrigerant evaporator comprising two sheet metal portions secured together in face engagement, at least one of said portions having an indentation therein forming a refrigerant conduit between said sheet metal portions, said conduit having an inlet and an outlet and an intermediate curved portion, said conduit having a substantially uniform cross section throughout its length, and an indentation formed in at least one of said sheet metal portions for providing a chamber in direct communication with said curved portion of said conduit, the entrance from said chamber to said curved portion being on a line tangential to the direction of flow of refrigerant through said curved portion whereby any slugs of liquid refrigerant flowing through said curved portion will tend to be thrown by their momentum from said conduit into said chamber.

8. A refrigerant evaporator comprising an upwardly extending sheet metal wall having a sinu-

ous conduit comprising a plurality of horizontal runs connected by return bends and having an inlet near the lower end thereof and an outlet near the upper end thereof, means providing chambers in direct communication with said conduit at a plurality of said bends, each of said chambers being arranged above and in direct communication with its respective bend in a line tangential to the direction of flow of refrigerant

in said respective bend whereby any slugs of liquid refrigerant flowing through said bends will tend to be thrown by their momentum from said bends into the respective chambers in communication therewith, the liquid refrigerant thrown into said chambers thereafter flowing by gravity back to said conduit.

LEONARD W. ATCHISON.
